UNITED STATES PATENT OFFICE.

ARTHUR EDWIN LEIGH SCANES, OF ASHTON-ON-MERSEY, ENGLAND, ASSIGNOR TO THE BRITISH WESTINGHOUSE ELECTRIC & MANUFACTURING COMPANY, LIMITED, OF LONDON, ENGLAND.

PUMP OR COMPRESSOR.

1,268,498.

Specification of Letters Patent. Patented June 4, 1918.

Application filed May 3, 1918. Serial No. 95,151.

To all whom it may concern:

Be it known that I, ARTHUR EDWIN LEIGH SCANES, a subject of the King of Great Britain, residing at Ashton-on-Mersey, England, have invented a new and useful Invention in Pumps or Compressors, of which the following is a specification.

This invention relates to air, gas or vapor pumps or compressors of the kind utilizing 10 a liquid in the form of a jet, spray or a succession of liquid leaves or pistons or the like as the working medium. Pumps of this kind as at present constructed usually derive their working liquid from a tank, commonly known as a seal tank, the liquid in which is at approximately atmospheric pressure.

Such pumps have the disadvantage that, as the weight of air or gases dealt with by 20 the pump increases with a resulting increase in the absolute pressure at the pump suction, the quantity of working liquid drawn into the impeller wheel nozzles or the like of the pump is decreased. This will be apparent when it is remembered that the quantity of working fluid taken by the pump varies with the difference in pressure between that existing at the suction of the pump and that of the space into which the 30 pump delivers.

According to this invention instead of an open seal tank a closed seal tank is used having a restricted outlet through which alone the gases or vapors compressed by the 35 pump and liberated from the liquid in said tank can escape.

By suitably controlling the effective area of the outlet from the closed seal tank the difference in pressure between that in the 40 seal tank and that in the air suction of the pump can be maintained substantially constant and the efficiency of the pump thereby increased. For example, in the case of a pump adapted to extract gases and non-condensable vapors from a space which it is desired to evacuate, when very little gases or vapors are being delivered by the pump atmospheric pressure will exist in the seal tank, while when gases or vapors are being 45 delivered in such quantity that the absolute pressure in the pump is atmospheric the pressure in said tank will be increased to approximately one atmosphere above atmospheric pressure.

50 In the accompanying drawings Figure 1

is a front elevation and Fig. 2 a side elevation of a seal tank constructed in accordance with this invention. Fig. 3 is a sectional view on a larger scale of a valve device shown in Figs. 1 and 2. Fig. 4 is a 60 diagrammatic view showing how a seal tank constructed in accordance with this invention would be connected up for use with a pump used for extracting air and non-condensable gases from a steam condenser. Fig. 65 5 is a diagrammatic development of the arrangement shown in Fig. 4.

In Figs. 1 and 2 the tank 4 is provided at its base with an inlet 5 adapted to be connected with the delivery of the pump 70 and with an outlet 6 through which the operating liquid from the tank 4 is supplied to the pump. Through another inlet 7 water is admitted to the tank for making up any loss occurring during operation of the 75 pump and for admitting cooling water to prevent an undue rise of temperature of the water in the tank.

Attached to the upper part of the tank 4 is a float chamber 8 which communicates 80 with the interior of the tank and contains a float 9 connected with a balanced valve or cock 10 of well known construction controlling an overflow from the tank 4. Said float 9 and valve 10 will maintain the level of the 85 water in the tank 4 at the desired height notwithstanding any make up or cooling water that may be admitted through the inlet 7.

The restricted outlet from the tank is shown at 11, its effective area being varied 90 automatically by means of a balanced valve device 12 subjected to the pressure existing in the tank 4 on the one hand and to the pressure existing at the air or gas inlet of the pump on the other hand. Said valve 95 is shown in section in Fig. 3 and comprises a cylinder 20 in which slides a piston 21 which controls the effective area of the restricted outlet 11 from the tank 4 communication with the latter being established 100 through the pipe 14. Said piston is subjected in one direction to the influence of an adjustable spring 22 and to the pressure existing at the air suction inlet of the pump with which the cylinder 21 is connected 105 through the outlet 23 and pipe 13. In the other direction the piston 21 is subjected to the pressure of the water and air in the seal tank admitted through the inlets 24 and 14.

110 In Fig. 4 the outlet 6 of the seal tank is

shown as being connected through a pipe 15 with the operating liquid intake of the pump 16, the delivery of the latter being connected by a pipe 17 with the inlet 5 to the tank. 5 The air or gas inlet of the pump 16 is connected through a pipe 18 with the air extraction port of a condenser 19.

The purpose of hand valve 24^a is to restrict the flow of water into and from the 10 body of valve 12 thus forming a dash pot to prevent hunting of the valve. This valve, however, will not be found to be absolutely necessary and in most cases will be omitted. Outlet 24' shown in Fig. 3 is provided for 15 the purpose of accommodating a drainage cock which may be supplied for the purpose of draining the valve chamber. This is not absolutely necessary and as a rule will not be provided in practice.

20 In operation if the weight of air and gases withdrawn from the condenser 19 through the pipe 18 is considerable the pressure at the air suction of the pump may approximate to atmospheric and will cause 25 the valve device 12 to maintain the outlet 11 closed or nearly so with the result that the air or gases will rapidly accumulate in the closed seal tank 4, but the resulting increase in the pressure in the seal tank will 30 cause the valve device 12 to enlarge the effective area of the restricted outlet 11 to such an extent that the pressure in the seal tank will not build up beyond the predetermined degree. The pressure on the operating 35 liquid in the tank will thus be maintained above the pressure existing at the air suction inlet to the pump which will insure a sufficient flow of water from the tank through the pump.

40 As the weight of the air and gases dealt with by the pump decreases a corresponding fall in the pressure will occur at the air suction of the pump and the pressure in the tank 4 will tend to fall. The valve device 45 12 will then act to reduce the effective area of the restricted outlet to such an extent as will insure the pressure in the seal tank 4 being maintained by the desired amount above the pressure in the air suction 50 of the pump 16.

In this application of the invention the normal difference of pressure between that existing at the air suction inlet of the pump and that on the liquid in the seal tank which 55 should obtain for the most efficient operation of the pump is approximately one atmosphere. This condition will exist when very little air or gases are being delivered by the pump and the effective area of the 60 restricted outlet from the seal tank will be such that as nearly as possible the pressure therein will not back up above two atmospheres absolute when the volume of air and gases delivered by the pump is considerable.

65 Fig. 5 is a diagrammatic development of

the arrangement shown in Fig. 4. The pump 16 here shown is of a well known form of rotary water extraction pump. In this type of pump water is taken from the tank 4 through the pipe 15 into the impeller 70 31 of the pump 16. Water is discharged from the impeller through the cone 32 into the collecting cone 33 entraining air arriving through the inlet pipe 18 from the condenser 19. The combined air and water mixture is then discharged through the pipe 17 into the tank 4 in which the air separates 75 out and is led through the pipe 14 into the balanced valve 12 which controls its release through the outlet 11 to the atmosphere. 80

In order that the operation of the apparatus may be clearly understood it may first of all be supposed that the cover of the tank 4 is removed, when a plant of a well known 85 character will be represented. Under full load conditions the pressure P^1 in the pipe 18 is approximately zero, P^2 representing the pressure (atmos.) at the surface of the water in the tank 4. Water flows from the 90 tank 4 through the pipe 15 into the impeller 31 which imparts to it an absolute pressure P^2 . The difference of pressure between P^2 and P^1 creates a flow of water through the cone 32. The water issuing at a high velocity from the cone 32 entrains the air in the pipe 18 and discharge it into the tank 4 where the air escapes to the atmosphere. It will be obvious that the head against the water flowing from the impeller 31 is the 95 100 pressure P^1 and it is also obvious that the quantity of water discharged by the impeller 31 will depend upon this head P^1 . If a heavy leakage of air should occur in the condenser 19 which increases the pressure 105 P^1 the head against the impeller 31 will increase, and as in the case of all centrifugal pumps the quantity of water discharged by the impeller will increase and therefore a less volume of air will be discharged by 110 the water jet issuing from the cone 32.

If the cover of the tank 4 is replaced so as to convert it into a closed seal tank the balanced valve 12 will be brought into operation and the pressure P^2 will be increased 115 above atmosphere by approximately the same amount as the pressure P^1 is above zero. For example when the plant is operating at full load and P^1 equals one-tenth of an atmosphere, the pressure P^2 will equal 120 one plus one-tenth atmospheres. This is brought about by the restriction in the amount of air allowed to escape through the air outlet 11 of the balanced valve device 12. If this heavy air leakage occurs in the 125 condenser 19 the pressure P^1 may rise to half an atmosphere and the pressure P^2 will then rise to one and a half atmospheres. Although in such a case the pressure head P^1 against the water jet has increased by 130

0.4 of one atmosphere the pressure of water at the inlet to the impeller 31 has also increased by 0.4 of an atmosphere and consequently the total head against the impeller 5 remains unaltered and therefore the same quantity of water will be discharged by the impeller and this will entrain approximately the same volume of air. The capacity of the pump is therefore greater than 10 if the tank 4 were open to the atmosphere.

When the plant is first started up and the pressure P^1 equals one atmosphere, pressure P^2 will rise to two atmospheres before the valve 12 opens and permits air to escape 15 from the tank through the outlet 11. As the vacuum increases and the pressure P^1 decreases correspondingly the pressure P^2 will also decrease until full load conditions are obtained.

20 The impeller 31 of the pump 16 may be driven in any convenient or usual way, such as by a steam turbine or an electric motor.

The invention has been described above with reference to Figs. 4 and 5 as applied to 25 the air pump of a steam condenser but it is to be understood that the invention is not limited in its application to such a use.

Having now particularly described and ascertained the nature of my said invention 30 and in what manner the same is to be performed, I declare that what I claim is:

1. In combination with a fluid-ejecting device with liquid as working medium and having a suction inlet for gas or air, a seal 35 tank having a gas and vapor outlet and connections whereby said device receives its actuating liquid from said tank and delivers liquid and gaseous fluid thereto, a make-up-liquid inlet to said tank and means 40 whereby the effective area of said gas and vapor outlet is automatically varied in accordance with the difference in pressures between that in the seal tank and that at the air or gas suction inlet of said ejecting 45 device.

2. In combination with a fluid-ejecting device or pump with liquid as working medium and having a suction inlet for fluid, a seal tank having an outlet through which

gases or vapors alone can escape, and connections between said ejecting device or pump and said tank whereby said device or pump receives its actuating liquid from said tank and delivers liquid and gaseous fluid thereto, and means whereby the effective 50 area of said gas and vapor outlet is automatically varied in accordance with the difference in pressures between that in the seal tank and that at the fluid inlet of said ejecting device or pump.

3. In combination with a fluid-ejecting device with liquid as working medium and having a suction inlet for fluid, a seal tank having a gas and vapor outlet and connections whereby said device receives its actuating liquid from said tank and delivers liquid and gaseous fluids thereto, a valved water-over-flow for said tank, the operation of which is dependent upon the opposing pressures existing in the tank and at the 55 fluid inlet of said ejecting device, and means whereby the effective area of said gas and vapor outlet is automatically varied in accordance with the level of water in said tank.

4. In combination with a fluid-ejecting device with liquid as working medium and having a suction inlet for gas or air, a seal tank having a gas and vapor outlet and a water over-flow, connections whereby said device receives its actuating liquid from said tank and delivers liquid and gaseous fluids thereto, a make-up-water inlet to said tank, means controlling the effective area of said water-over-flow, the operation of which is 60 dependent upon the difference in pressure between that in the seal tank and that at the air or gas inlet of said ejecting device, and means whereby the effective area of said gas and vapor outlet is dependent upon the 65 water level in said tank.

In testimony whereof I have hereunto subscribed my name this seventh day of April, 1916.

ARTHUR EDWIN LEIGH SCANES.
